UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,073,162.

Specification of Letters Patent. Patented Sept. 16, 1913.

Application filed March 10, 1913. Serial No. 753,220.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging having a preliminary compression resisting member.

In the accompanying drawings forming a part of this specification Figure 1 is a side elevation partly in vertical longitudinal section on line 1—1 of Fig. 2 of a draft rigging embodying my invention. Fig. 2 is a plan view partly in horizontal section on line 2—2 of Fig. 1. Fig. 3 is a perspective view of the rear end of the shell of the draft gear. Fig. 4 is a perspective view of the preliminary spring holder. Fig. 5 is a perspective view of one of the preliminary springs.

In the drawings 6, 6 represent draft members or parts of the car frame to which the draft rigging is applied, 7 the end sills, 8, the buffer block, 9 the draw bar carry iron, 10 the tie plate, 11 the draw bar, 12 the draft yoke, forwardly provided with a hollow head 13 laterally slotted to receive the coupler key 14, which passes through the same and through the draw bar 11, 15 front stop members having the stop shoulders 16, 16 and limiting stop shoulders 17, 17, 18, 18 rear stop members provided with the stop shoulders 19, 19.

The U-shaped yoke strap 20 of the draft yoke 12 is provided at its inner rear end with the filler block 21, between which and the front follower 22 and within the lateral opening 23 of the draft yoke is mounted the draft gear 24. The draft gear 24 comprises a shell 25, friction mechanism 26 and springs 27, 27 within the shell, the springs 50 being forwardly seated against the friction mechanism and rearwardly seated against the friction shell, the parts within the shell being held in assembled position by the connecting rod 28 extending through the friction mechanism at its forward end, and be-

ing secured at its rearward end by the nut 28^a, which is received within the recess 29 at the rear end of said shell.

The shell is provided at its rearward end with a box-like member 30, which is preferably integral with the shell, having the rearward opening 31 and recesses 32, 32 at either side of said opening, said recesses being adapted to receive the ends of preliminary springs 33, preferably composed of a plurality of flat springs, the same passing intermediate their ends through the transverse slot 34 provided in the block like preliminary spring holder 35. The rear face of the said slot 34 is preferably convex from side to side. The forward and rear faces 36 and 37 respectively of the preliminary spring holder 35 are preferably convex, as illustrated in Fig. 4 of the drawings. The rear face of the preliminary spring holder 35 is seated against the inner end of the draft yoke 12, and preferably against the filler block 21.

The inner forward face 38 of the box-like member 30 at the rear of the shell is preferably concave so as to permit the preliminary springs 33, to be forwardly flexed on forward movement of the preliminary spring holder 35. Within each slot 32 at the sides of said box-like member 30 and along the rearward face thereof, and removed from the end of said slot like member there is provided in preferable construction a reinforcing vertically disposed bolt 39, which preferably passes through the said box-like member, each bolt being provided at its one end with a head 40 and at its other end with a nut 41.

The preliminary spring holder is seated against the inner end of the draft yoke at its rear face, and on forward movement of the draft yoke in pulling movement of the draft rigging the preliminary springs 33, passing through the preliminary spring holder 35 are drawn forwardly intermediate the ends of the springs, the ends being seated, as hereinbefore described, within the slots 32, 32.

The box-like member 30 is laterally provided with slots 43 through which the springs are inserted within the said box-like member in assembling the parts of the gear. The flexing movement of the springs is limited when the forward face 36 of the spring holder 35 engages the rear end of the

shell, and thereupon the shell is drawn forwardly, compressing the parts within the shell against the front follower 22. On rearward movement of the draft yoke in 5 buffing movement of the draft rigging the preliminary springs 33, remain in their normal position, said position being illustrated in Fig. 2 of the drawings.

It will be obvious that the preliminary 10 springs in the arrangement hereinbefore described insure an easy preliminary movement of the draft gear in the pulling action of the draft rigging, and therefore afford means of imparting an easy movement to 15 the car in connection with which the same is employed.

I claim:

1. In a draft rigging, in combination, a draw bar, a draft yoke, stop members, a 20 shell, compression resisting parts within the shell, a preliminary spring comprising flexible plates, a preliminary spring holder, the said shell being rearwardly provided with a box like recess to receive the preliminary 25 spring, further recesses at either side of said box-like recess to receive the ends of the preliminary spring, and hold said ends in a fixed position, a preliminary spring holder engaging the preliminary spring within said 30 recess, said preliminary spring holder being in engagement with the draft yoke.

2. In a draft rigging for railway cars, in combination, a draft yoke and a draft gear, the draft gear having a shell, compression 35 resisting parts within the shell, the said shell being rearwardly provided with a box-like opening, flat springs within said open-

ing, and means of securing said flat springs at either end, a preliminary spring holder, a slot in the same through which the said flat springs are passed, the said preliminary spring holder engaging with the draft yoke on forward movement of said yoke.

3. In combination, a draft yoke and a draft gear, the draft gear comprising a 45 shell, compression resisting members within the shell, a box-like member at one end of said shell, slots within said box-like member, a preliminary spring engaging within said slots, a preliminary spring holder in engagement with said springs, said preliminary spring holder comprising a box like member provided with a slot to receive said preliminary spring, said preliminary spring holder being in engagement with the draft 55 yoke in forward movement thereof.

4. In a draft gear, a shell, compression resisting parts within the shell, a preliminary spring and a preliminary spring holder, the shell being provided at one end with a 60 box-like member, means within said member for engaging the preliminary spring at either end, a preliminary spring holder, a slot through said holder adapted to receive the preliminary spring therethrough, the 65 rear face of said slot being curved to permit the flexing of said spring therein, the said spring holder being adapted to engage with the draft yoke.

JOHN F. O'CONNOR.
